UNITED STATES PATENT OFFICE.

NEIL SINCLAIR, OF OAKLAND, CALIFORNIA.

EXTENSIBLE BED.

1,287,120.

Specification of Letters Patent. Patented Dec. 10, 1918.

Application filed May 8, 1918. Serial No. 233,339.

To all whom it may concern:

Be it known that I, NEIL SINCLAIR, a citizen of the United States, residing at Oakland, in the county of Alameda and State of California, have invented new and useful Improvements in Extensible Beds, of which the following is a specification.

My invention relates to improvements in extensible beds and has special reference to 10 the means for balancing the weight of the mattress and frame therefor so as to render it easy to swing the latter from a vertical to a horizontal position, or in a reverse direction.

15 One object of the invention is to provide such means which will be compact in form, and which, in the movement of the bed, will not become unduly stretched.

In the accompanying drawing, Figure 1 20 is a perspective view of the head portion of a bed embodying my invention and in a position intermediate between its extended and its collapsed positions; Fig. 2 is a broken side view of the head of the bed in 25 its collapsed position; Fig. 3 is a similar view thereof in its extended position; Fig. 4 is a detail front view, certain parts being shown in section.

Referring to the drawing, 1 indicates the 30 head of an extensible bed, the top of which is adapted to be pivoted, as by an angle bar 2, on the edge of the closet door. This feature, however, forms no part of my present invention. To the side members 3 of said bed head are secured rear portions of plates 35 or brackets 4. Said plates or brackets may thus be considered as forwardly extending parts thereof. To the upper front corners of said brackets are pivoted, by bolts 5, castings 6, which are curved so that their ends 40 fit closely against the outer sides of the tubular side members 7 of a mattress frame 8 of ordinary construction and are bolted thereto. A rod 9 extends transversely between the brackets 6 and its ends are secured 45 in the lower front corners thereof. The bolts 15 which secure the upper ends of the castings 6 to the side members also extend through plates 11, which fit closely against the inner sides of said side members, and 50 also extend through the outer ends of side members 12 of a U-shaped frame 13, the central member 14 of which extends transversely beneath the mattress frame. Said side members 12 are also pivotally secured 55 near their centers to ends of links 16, other

ends of which have apertures through which the rod 9 extends loosely. Helical springs 17 terminate in hooks 18, 19, the hooks 18 engaging holes in a transverse bar 21 forming part of the mattress frame and the hooks 19 engaging the central member 14 of the U-shaped frame. Said central member 14 has secured thereto depending feet 21, 60 which, in the extended position of the bed, 65 are adapted to rest upon the ground and additionally support the mattress frame.

By comparing the position of the mattress frame in Fig. 2 with its position in Fig. 3 it will readily be seen that, as the bed is 70 lowered for use, the springs 17 are stretched, and, consequently, said springs counterbalance the weight of the bed while it is being lowered. For the same reason they assist 75 in raising the bed to its collapsed position.

The brackets or plates 4 are curved outwardly in the center so as to more readily accommodate the portion of the bed clothes at the head of the bed and the pillows.

I claim:

1. The combination of a bed head having forwardly extending portions, a mattress frame between said forwardly extending portions and pivoted thereon, a frame, side members of which are pivotally connected 85 at their free ends to said mattress frame, a link limiting the movement of said frame from a forwardly extending portion of said extension, and a spring connected at one end to said frame and at the other end to the 90 mattress frame.

2. The combination of a bed head having forwardly extending portions, a mattress frame between said forwardly extending portions and pivoted on upper portions 95 thereof, a frame, side members of which are pivotally connected at their free ends to said mattress frame, a link limiting the movement of said frame from a forwardly extending portion of said extension, and an 100 extensible spring connected at one end to said frame and at the other end to the mattress frame nearer the head of the bed than the mattress frame pivots.

3. The combination of a bed head having forwardly extending portions, a mattress frame between said forwardly extending portions and pivoted on upper portions thereof, a U-shaped frame the side members 110 of which are pivotally connected at their free ends to said mattress frame, a link limiting the movement of said U-shaped frame

- from a forwardly extending portion of said extension, and a spring at each side of the bed connected at one end to said frame and at the other end to the mattress frame.
- 5 4. The combination of a bed head having forwardly extending portions, a mattress frame between said forwardly extending portions and pivoted on upper portions thereof, a rod extending between and se-
10 cured to forwardly extending portions of said extensions, a frame having portions

arranged to rest upon the floor when the bed is extended for use, and side members of which are pivotally connected at their free ends to said mattress frame, links piv- 15 otally connected each at one end to mediate portions of said side members, and at the other end connected to said transverse rod, and a spring connected at one end to said frame and at the other end to the mattress 20 frame.

NEIL SINCLAIR.
